CLAIM

The ornamental design for a packaging device for a windscreen wiper, as shown and described.

DESCRIPTION

The sole FIGURE is a bottom, front, and right side perspective view of a packaging device for a windscreens wiper, showing our design.

The flange, ledge, and recess surfaces of the packaging device for a windscreens wiper shown in the sole figure are only curved around the Z-axis such that the flange, ledge, and recess surfaces are curved in the X-Y plane. When viewed from a front elevational view, the Z-axis is perpendicular to the flange, ledge, and recess surfaces. Thus, the flange, ledge, and recess surfaces of the packaging device for a windscreens wiper shown in the sole figure are not curved in the Z-X and Z-Y planes.

The broken lines are included for the purpose of illustrating portions of the packaging device for a windscreens wiper that form no part of the claimed design.
